UNITED STATES PATENT OFFICE.

AARON W. CLARK, OF WINSLOW, ARKANSAS.

CLOSURE FOR MAIL-BAGS.

984,540.

Specification of Letters Patent. Patented Feb. 21, 1911.

Application filed September 3, 1909. Serial No. 516,015.

To all whom it may concern:

Be it known that I, AARON W. CLARK, a citizen of the United States, residing at Winslow, in the county of Washington, 5 State of Arkansas, have invented certain new and useful Improvements in Closures for Mail-Bags; and I do hereby declare the following to be a full, clear, and exact description of the invention, such as will enable others skilled in the art to which it 10 pertains to make and use the same.

This invention relates to closures for mail bags.

The object of the invention is to provide 15 an improved closure designed especially for mail bags, but which may be applied with equal facility to other bags and like receptacles, and which will be simple in construction and convenient in use, being easily fastened and unfastened, of great strength, and practically immune against accidental opening.

With the above and other objects in view 20 the invention consists in the details of construction and in the arrangement and combination of parts to be hereinafter fully described and set forth in the claims.

In describing the invention in detail reference will be had to the accompanying 25 drawings in which like characters of reference denote like parts in the several views, and in which,

Figure 1 is a plan view of a mail bag constructed with the improved closure; Fig. 35 2, a view similar to Fig. 1 with the upper locking plate removed and thrown back; Fig. 3, a view similar to Fig. 1 showing the bottom of the closure; Fig. 4, a view of a fragment of the top of the mail bag showing 40 the manner of forming folds which constitute the closure and the location of the locking studs with relation to the folds; Fig. 5, an enlarged sectional view on the line 5—5 45 of Fig. 1; and, Fig. 6, an enlarged section on the line 6—6 of Fig. 4.

Referring to the drawings 1 indicates the fabric body or side wall of the mail bag which has its top edge formed with a series of similar arcuate scallops 2, in spaced 50 relation to each other, a straight edge 3 connecting the edges of the adjacent arcuate scallops. The upper end of the fabric body 1 is then plaited to form the alternate large and small folds 4 and 5 respectively, the line 55 of folds between the small fold 5 and the large fold 4 on one side being inclined to

the vertical axis of the bag and the line of folds between said small fold and the adjacent large fold on the opposite side being parallel to the vertical axis of the bag. To 60 produce a natural tendency to the upper end of the fabric body to assume the plaited status illustrated in Figs. 1, 2 and 3 the following structure is resorted to:—First the large and small folds are reinforced a desired distance inwardly from the top edge 65 of the fabric side of the bag in any suitable manner, preferably by applying a layer of sole leather 23 thereto and riveting same to the fabric by means of the rivets 8, it being understood that the line of folds 6 and 7 are not reinforced, or if reinforced it is to a much less extent than the folds 4 and 5, whereby a different degree of flexibility is had between the folds 4 and 5 and the 70 lines of fold 6 and 7; secondly, a layer of flexible material 22 is disposed over the line of fold 7, and has its terminals secured between the leather reinforcing 23 of the folds and the fabric body 1; a considerable portion 75 of said layer 22 being located between adjacent edges of the reinforcing layers 23 so that when said folds 4 and 5 tend to move inwardly the distance between the edges of the reinforcing leather layers 23, adjacent 80 the line of fold 7 will decrease and the portion of the layer 22 disposed between said edges will be compressed and forced outwardly so as to protrude between said edges and at the same time serve as an abutment 85 to effectually terminate said tendency of the folds to move outwardly; third, there is disposed over the line of fold 6 on the inner face of the fabric 1 a strengthening strip 24 and the folds 4 and 5 are permanently 90 secured together a slight distance from the line of folds 6 by the rivets 25 which pass through the strengthening strip 24, the fabric 1 and the leather reinforcing layers 95 of the fold. It will thus be obvious that 100 the folds 4 and 5 will always be maintained angularly disposed with relation to each other, even when not in a completely folded state and it will be further apparent that it will require but the slightest effort to move 105 said folds to a completely folded state for the purpose of closing the mouth of the bag. It will also be apparent that when the mouth end of the fabric body 1 is disposed in a plaited state the large folds 4 will overlie 110 the small folds 5 and the arcuate edges of said folds will constitute the annular wall

of an aperture located centrally of the bag around which the plaits are disposed.

Secured to each of the large folds 4 on the under side thereof is a latch which comprises 5 a stem portion 9 secured directly to the fold and extending beyond the edge thereof and located adjacent the inclined line of folds 6. The outer or free end of said latch stem has formed thereon the downwardly and up- 10 wardly projecting locking studs 10 and 11, which when the top of the bag is disposed in a plaited state lie in annular formation directly within the arcuate edges of the folds.

Secured to one of the large folds 4 on its 15 under face by means of a strap 12 is a locking plate or keeper 13; said plate or keeper being of circular formation and the strap 12 of such length that said plate or keeper will be disposed directly beneath the circular 20 aperture formed by the arcuate edges of the folds of the plaits. Projecting centrally from the top face of the plate 13 is a stud 14 which has a staple 15 mounted in its outer end, while an annular groove 16 is formed 25 in the top face of the plate 13 and surrounds said stud 14.

An upper locking plate 17 adapted to lie in vertical alinement with respect to the locking plate 14 is secured to the top face of 30 one of the folds 4 by means of a strap 18. An annular recess 19 is formed centrally in the lower face of the plate 17 and a slot 20 is cut through the inner wall of the recess 19 passing out through the top face of the said 35 plate. A suitable handle 21 for supporting the bag as an entirety is pivotally connected with said plate 17.

The manner of operating the closure just described will be obvious.

40 Assuming the bag to be full and ready for locking the folds 4 are disposed over the folds 5 to produce a series of overlying plaits. The staple 15 is then gripped and raised to move the keeper 13 upwardly, 45 when the studs 10 will enter the annular groove 16. The upper keeper 17 is then

moved to a position in vertical alinement with the keeper 13 when the staple 15 will pass through the slot 20 and the studs 11 into the annular recess 19. A lock 21 is then 50 secured to said staple and a permanently locked condition of the closure effected, by reason of the non-detachable engagement existing between the keepers 13 and 17 and the studs 10 and 11. The manner of opening 55 the closure will be obvious; it being only necessary to remove the lock 22 from the staple 15 when an easy disengagement of all the parts can be readily effected.

What is claimed is:

1. A bag closure comprising in combination a bag body, a series of locking devices secured around the edge of the mouth thereof, a pair of keeper plates each having their adjacent faces recessed for the reception of 65 said locking devices when disposed in vertical alinement on opposite sides of said locking devices; and means for locking said keepers together when said locking devices are disposed in the recesses of said keeper 70 plates.

2. A bag closure comprising in combination, a bag body, a series of catches secured around the edge of the mouth thereof; said catches comprising a stem portion fixed to 75 said bag body and a projecting terminal portion provided with upwardly and downwardly disposed studs, a lower keeper having an annular groove in its upper face adapted to receive the downwardly projecting studs of the catches, an upper keeper provided with a recess in its lower face adapted to receive the upwardly projecting studs of the catches; and means for locking 80 said keepers together when in engagement 85 with the studs of said catches.

In testimony whereof, I affix my signature, in presence of two witnesses.

AARON W. CLARK.
